NISHI KANTA SARKAR, OF CALCUTTA, INDIA

RAIN WATER PIPE

Application filed September 21, 1928, Serial No. 307,495, and in British India April 30, 1928.

This invention relates to rain water pipes and has for its object to provide a rain water pipe which can be secured in position more cheaply and in a better manner mechanically than rain water pipes are now fixed.

Another object is to provide a rain water pipe which needs no separate brackets, collars or fixing bands requiring nails on either side, and a still further object is to avoid the use of pairs of cast perforated lugs or ears on a rain water pipe through which spikes or the like have to be driven, because these lugs or ears are likely to get broken when the spike is driven.

15 Rain water pipes are usually made of cast iron. If made of cast iron one common method of fastening the pipe to a wall is to provide a pair of cast lugs or ears one on either side of the pipe which are pierced to take the spike. This needs two spikes to secure the pipe in position. A cast iron lug is a brittle projection and there is a great danger that in driving a spike through the hole therein and into a wall the hammer may 20 hit and break off the lug. Further owing to two lugs at least being needed, one on either side of the rain water pipe, and owing to the difficulty of driving spikes in the exact position desired in a masonry wall it often 25 occurs that the spikes go out of position in driving or become crooked with the result that a side strain and eccentric pull is thrown on the cast iron lugs which they are quite unfitted to resist, being of thin cast iron.

30 Sometimes rain water pipes are fixed by using securing bands which are placed around the pipe and secured by driving a spike there-through on either side of the pipe. Such bands hold the pipe in place but usually 35 do not support the different length which accordingly nest into each other, with the result that the lowest pipe carries the weight of all the other pipes thereon, which weight may be transferred thereto unevenly owing 40 to point contact.

45 In either of these cases each length of the pipe needs at least two spikes to hold it, and these spikes may or may not be efficient in helping to carry the weight of the pipe length.

Now according to the present invention a single spike or the like may be used for supporting each length of pipe. This method accordingly reduces the number of spikes or the like to half, thus reducing cost and labour.

55 The spike is moreover driven on the centre lines of the rain water pipe and hence tends to carry the pipe suspended therefrom in the most efficient manner. There can thus be no side strain owing to the weight being carried by one of two spikes which spike is to one side of the pipe.

60 In order to make the rain water pipe more stable in its position small blocks, projections or feet may be provided. These in cast iron pipes may be cast on, but owing to their small size and owing to their not needing to have spikes driven therethrough these small 65 projections are not so likely to be damaged or broken off as the large ears or lugs on ordinary cast iron pipes.

69 Further objects and features will be apparent from the following description.

75 The invention consists of an improved rain-water pipe of the spigot and socket type adapted to be suspended from or supported by a single simple nail, spike hold-fast or the like supporting means, characterized by this that the socket which is intended, when 80 in use, to be at the upper end of the pipe length is provided with an aperture or slot in the walls thereof for the introduction therein of or attachment therefrom to the 85 supporting means, and these walls give sufficient clearance between them and the spigot end of the next length of pipe which is to be introduced into the said socket end to allow of the pipe being thus supported and thereafter the next length of piping thereabove being introduced.

90 It also includes a rain-water pipe of spout length of the spigot and socket type having a perforation slot or aperture in the socket and which is adapted to be supported thereby from or upon a single simple nail, spike hold-fast or the like simple supporting means from said socket end, characterized by this 95 that the perforated, slotted or apertured part of the pipe or spout length is a part which is 100

kinked out or off-set from the socket part by such amount that the head of the nail, spike or other supporting means intended to be driven into the wall to support the pipe shall not prevent the end of the next section of the 5 pipe above from being fitted into the section already erected and fixed.

The pipe may be one in which the hole, slot or aperture is made adjacent to the top of the pipe and an intermediate attaching 10 means, for example a flexible piece of wire, or a metal loop or hook, or a chain, is engaged in said hole, slot or aperture and is adapted to be hooked over or to engage the 15 supporting nail, spike or the like supporting means to support the pipe or spout length. Alternatively the hole, slot or aperture made in the socket of the pipe may be adapted to support the pipe directly from a supporting 20 means with a flattened head.

The pipe according to this invention may have an apertured and slotted socket and in addition a foot or staying surface, for example a block, projection or projections, with a flat portion thereon adapted to engage the 25 wall to which the pipe or spout is to be fixed for the purpose of steadyng the pipe against the wall, enabling it to hang vertically from its nail or the like and to prevent, by frictional contact with the wall, any tendency 30 to side movement.

The pipe is one which alternatively is adapted to be supported by having an aperture therein enabling it to be wired to a supporting nail or the like.

The invention includes a pipe having in combination a socket part at its upper end to engage the spigot or lower end of the pipe or spout length above an aperture in the socket part in a portion thereof offset to give 35 clearance between the inner side of said offset portion and the spigot or pipe part which is to enter the socket, said clearance being sufficient to enable the head of the nail or supporting means, or attachment hereto, to lie between the said part and the said spigot or end.

The invention will now be described with reference to the accompanying drawings, in which:—

Figure 1 is a vertical cross section through a pipe.

Figure 2 is a horizontal cross section on line A—A of Figure 1, and

Figure 3 is a modification indicating a different manner of supporting the pipe or spout using a flexible member for holding the same to the spike or the like.

In these drawings the pipe or spout 1 is provided with a socket 2 into which the spigot end of the pipe or spout length above is intended to be an easy fit.

In this socket end a slot 3 or other suitable aperture 4 may be made so that the pipe or spout may be hung directly from a spike,

nail or hold-fast 5 driven into the wall on the center-line of the pipe. The socket part 2 will be made sufficiently large or have sufficient clearance to allow for the head of the said spike or the like to remain in the space 70 between the inner side of the socket and the outer side of the spigot end.

The socket part of the pipe or spout need not necessarily be made circular in plan but might on the contrary be provided with a projection or bulge in that part of the socket in which the hole 4 or slot 3 is made. This bulge or projection might be flattened on its outer side at the part which rests against the wall so that the said bulge or projection serves 75 the two-fold purpose of allowing ample clearance for the spike head or the like and also at the same time serves to steady the pipe or spout length against the wall.

To steady the pipe or spout against the 80 wall and also to support it away from the wall at a distance which will cause the pipe or spout to hang vertically from its spike or nail the projections 6, 6, are provided which engage the wall surface 7. These 85 projections steady the pipe owing to the frictional contact with the wall surface. It will be observed that the size and projection of these parts 6, 6, is considerably less than that of the part 8 (shown in dotted lines on Fig. 90 2) which parts indicate a known form of bracket which has sometimes been cast onto a length of cast iron rain water piping so that the pipe may be secured to the wall by an extra spike 9. These known brackets 8 have 95 usually been used in pairs in spite of the fact that it is very difficult to drive two spikes evenly and at desired positions into a masonry wall. In using these known types of brackets 100 8 difficulty has been often experienced owing to the danger of the brackets being broken off whilst the spikes are being driven through them. Figure 3 shows an alternative method of supporting the spout according to which the spout is supported by a 105 flexible means such as a stiff iron wire 10 which is passed around the pin 11, threaded through the hole 4 in the socket part and attached in any convenient way to the spike 5a. It will be noticed that in this manner 110 of support the clearance needed between the spigot end and the socket is less than that needed when the spout is hung directly to a spike or the like unless the head of the spike is made very flat indeed.

Having now particularly described and ascertained the nature of my said invention and in what manner the same is to be performed, I declare that what I claim is:—

1. An improved rain-water pipe of the 115 spigot and socket type having an aperture in the socket end, headed supporting means engaged through said aperture for supporting said part, and said apertured part being offset from the main part an amount suf- 120 130

ficient to allow the headed portion of the supporting means to be positioned further from the axis of the pipe than the inner surface of the main portion of the pipe whereby to permit the spigot end of the next above pipe being fitted into the socket end of the pipe already erected and fixed and being spaced from the headed portion of the supporting means.

5 2. A device of the character described including in combination, a single supporting means, a pipe the lower end of which is smooth while the upper end is enlarged to form a socket, the walls of the socket being provided with an aperture of a size to enable the pipe to be engaged over and hung upon the supporting means, said walls being also arranged to give sufficient clearance between them and the smooth end of the next length of pipe so that the latter can be introduced 10 into the socket and supported and also positioned in spaced relation to the outer end of the supporting means.

15 3. A rain-water pipe according to claim 2, in which the aperture made in the socket of the same is adapted to support the pipe directly from a supporting means having a flattened head.

20 4. A cast iron rain-water pipe according to claim 2 having in addition a staying surface 30 in the form of a projection provided with a flat portion thereon adapted to engage the wall to which the pipe is to be fixed for the purpose of steadyng the pipe against the wall, enabling it to hang vertically from its 35 supporting means to prevent, by frictional contact with the wall any tendency to side movement.

40 In testimony whereof I hereto affix my signature this 10th day of August, 1928.
